UNITED STATES PATENT OFFICE.

WILLIAM T. HULSCHER, OF BATTLE CREEK, MICHIGAN.

CUTTING MACHINE.

Application filed June 25, 1923. Serial No. 647,653.

To all whom it may concern:

Be it known that I, WILLIAM T. HULSCHER, a citizen of the United States, residing at Battle Creek, county of Calhoun, State of Michigan, have invented certain new and useful Improvements in Cutting Machines, of which the following is a specification.

This invention relates to improvements in cutting machines.

10 My improved cutting machine is especially designed by me for cutting cotton wadding although readily adapted and desirable for use in cutting resilient fibrous material and fabrics and the like.

15 The main object of the invention are:

First, to provide an improved cutting machine adapted for the cutting of cotton wadding which produces clean-cut edges in the material and is of large capacity.

20 Second, to provide an improved machine for cutting resilient material which is simple and economical in structure and very easily operated.

Further objects, and objects relating to 25 structural details, will definitely appear from the detailed description to follow.

I accomplish the objects of my invention by the devices and means described in the following specification. The invention is 30 clearly defined and pointed out in the claims.

A structure which is a preferred embodiment of my invention is clearly illustrated in the accompanying drawing, forming a part of this application, in which:

35 Fig. I is a side view partially in vertical longitudinal section on a line corresponding to line 1—1 of Fig. II.

Fig. II is a fragmentary top plan view, one end only being illustrated the other end 40 being a duplicate thereof, the cutter being shown in operative position.

Fig. III is a cross section through the cutter standard and knife or cutter blade.

In the drawing similar reference characters refer to similar parts throughout the several views.

Referring to the drawing, I provide a base 1 having suitable legs, the base and legs being preferably an integral casting.

50 The top of the base is machined to provide a bearing surface for the cutter base 2. This cutter base is provided with a bearing pivot 3, the base 1 having a series of bearings 4 adapted to receive this pivot.

55 A groove 5 extends longitudinally of the base as a guide for the pivot facilitating the

shifting of the pivot from one bearing to another, the groove extending between and opening to the bearings so that the pivot may be withdrawn from the bearing and 60 slid along in the groove by which it is guided to the succeeding pivot.

I provide a pair of clamping plates 6 and 7, the bottom clamping plate 6 being spaced from the base 5 by means of the block 8, it being securely bolted to the base. These spacing blocks carry the guide rods 9 for the top clamping plate 7. Clamps 10 are provided for the top clamping plate, the clamps illustrated being the well-known cabinet makers' type of clamps which were 70 found satisfactory.

The top clamping plate is provided with set screws 11 which may be used to hold the top clamping plate in clamped up position when it is desired to move the clamps.

75 A plurality of layers of cotton wadding is indicated at 12. These clamping plates are provided with aligned pattern or guiding holes 13, the particular structure being designed to cut circular disks used in milk strainers. The cutter standard 14 is mounted on the cutter base 2, it being adapted to form a guide for the cutter blade 15.

This blade is reciprocated by the motor, indicated at 16, the motor being mounted 80 upon the standard. The motor base is provided with a handle 17 by means of which the cutter may be advanced to the work, being guided in its movement by the pattern openings in the clamping plates and the base 2 swinging about its pivot.

85 The knife reciprocates across the edges of the clamping plates which serve as shear members. The pattern openings 13 are connected by the slots 18 so that the cutter may be readily shifted from one pattern opening 90 to the succeeding pattern opening.

95 With this arrangement of parts, the resilient material, such as cotton wadding, may be rapidly cut with very clean cut edges to the work.

100 Having thus described my invention, what I claim as new and desire to secure by Letters Patent, is:

1. In a machine for cutting wadding, the combination with a base provided with a series of spaced pivot bearings and a pivot 105 guiding groove extending between and opening to said bearings, a bottom clamping plate mounted on said base in spaced relation thereto, guide rods projecting above

105

110

said bottom clamping plate, a top clamping plate mounted on said rods for vertical adjustment, clamping means for said clamping plates, a cutter base provided with a pivot pin adapted to be engaged in said bearings in said base plate, said groove in said base constituting a guiding means for said pivot facilitating the shifting from one bearing to another, a standard carried by said cutter base and constituting a cutter guide, a cutter reciprocating in said guide, and a cutter driving means mounted on said standard, said clamping plates being provided with guide openings and constituting shear members 10 coating with said cutter, there being communicating slots between said guide openings permitting the shifting of the cutter from one to another in succession.

2. In a machine for cutting wadding, the combination with a base provided with a series of spaced pivot bearings, a bottom clamping plate mounted on said base in spaced relation thereto, guide rods projecting above said bottom clamping plate, a top clamping plate mounted on said rods for vertical adjustment, clamping means for said clamping plates, a cutter base provided with a pivot pin adapted to be engaged in said bearings in said base plate, a standard 20 carried by said cutter base and constituting a cutter guide, a cutter reciprocating in said guide, and a cutter driving means mounted on said standard, said clamping plates being provided with guide openings and constituting shear members 25 coating with said cutter, there being communicating slots between said guide openings permitting the shifting of the cutter from one to another in succession.

3. In a machine for cutting wadding, the combination with a base provided with a series of spaced pivot bearings and a pivot guiding groove extending between and opening to said bearings, a pair of coating 40 clamping plates, a cutter base provided with a pivot pin adapted to be engaged in said bearings in said base plate, said groove in said base constituting a guiding means for said pivot facilitating the shifting from one bearing to another, a standard carried by 45 said cutter base and constituting a cutter guide, a knife reciprocating in said guide, and a knife driving means mounted on said standard, said clamping plates being provided with guide openings and constituting shear members 50 with which said knife coacts, there being communicating slots between said guide openings permitting the shifting of the cutter from one to another in succession.

4. In a machine for cutting wadding, the combination with a base provided with a series of spaced pivot bearings, a pair of coating clamping plates, a cutter base provided with a pivot pin adapted to be en-

gaged in said bearings in said base plate, a standard carried by said cutter base and constituting a cutter guide, a knife reciprocating in said guide, and a knife driving means mounted on said standard, said clamping plates being provided with guide openings and constituting shear members with which said knife coacts, there being communicating slots between said guide openings permitting the shifting of the cutter from one to another in succession. 70

5. In a machine for cutting wadding, the combination with a base provided with a series of spaced vertically disposed pivot bearings and a pivot guiding groove extending between and opening to said bearings, a bottom clamping plate mounted on said base in spaced relation thereto, guide rods projecting above said bottom clamping plate, a top clamping plate mounted on said rods for vertical adjustment, clamping means for 80 said clamping plates, a cutter base provided with a pivot pin adapted to be engaged in said bearings in said base plate, said groove in said base constituting a guiding means for said pivot facilitating the shifting from one bearing to another, and a cutter carried by said cutter base, said clamping plates being provided with guide openings for said cutter, there being communicating slots between said guide openings permitting the shifting of the cutter from one to another. 85

6. In a machine for cutting wadding, the combination with a base provided with a series of spaced vertically disposed pivot bearings, a bottom clamping plate mounted on said base in spaced relation thereto, guide rods projecting above said bottom clamping plate, a top clamping plate mounted on said rods for vertical adjustment, clamping means for said clamping plates, a cutter base provided with a pivot pin adapted to be engaged in said bearings in said base plate, and a cutter carried by said cutter base, said clamping plates being provided with guide openings for said cutter, there being communicating slots between said guide openings permitting the shifting of the cutter from one to another. 90

100

7. In a machine of the class described, the combination of a base provided with a series of spaced pivot bearings and a pivot groove extending between said opening to said bearings, a pair of coating clamping plates, a cutter base provided with a pivot pin adapted to be engaged in said bearings in said base plate, said groove in said base constituting a guiding means for said pivot facilitating the shifting from one bearing to another, and a cutter carried by said base 115

120

member, said clamping plates being provided with guide openings for said cutter, there being communicating slots between said guide openings permitting the shifting of the cutter from one to another. 125

130

8. In a machine of the class described, guide openings for said cutter, there being the combination of a base provided with communicating slots between said guide 10 openings permitting the shifting of the cutter from one to another.

5 provided with a pivot pin adapted to be engaged in said bearings in said base plate, and a cutter carried by said base member, said clamping plates being provided with

In witness whereof I have hereunto set my hand and seal.

WILLIAM T. HULSCHER. [L. s.]
